UNITED STATES PATENT OFFICE.

PAUL E. NORRIS, OF SWISSVALE, PENNSYLVANIA, ASSIGNOR TO WILLARD STORAGE BATTERY COMPANY, OF CLEVELAND, OHIO, A CORPORATION OF WEST VIRGINIA.

LUG-CLEANER AND PLATE-SPLITTER.

1,372,824.

Specification of Letters Patent. Patented Mar. 29, 1921.

Application filed April 9, 1920. Serial No. 372,595.

To all whom it may concern:

Be it known that I, PAUL E. NORRIS, a citizen of the United States, residing at Swissvale, in the county of Allegheny and 5 State of Pennsylvania, have invented a certain new and useful Improvement in Lug-Cleaners and Plate-Splitters, of which the following is a full, clear, and exact description.

10 This invention relates to a machine for cleaning the lugs of double storage battery plates and splitting the plates into single or individual plates so as to adapt them for storage battery use. The machine constituting the subject matter of the present invention is an improvement over a machine for cleaning and cutting the lugs of single plates claimed in a copending application, Serial No. 246,244, filed July 22, 1918.

20 In my prior application storage battery plates are placed in a magazine at one end of the machine and are carried therethrough by a continuously moving conveyer, past a saw and milling cutters which respectively 25 cut off the outer ends of the lugs and mill the side faces thereof so that when the plates are delivered at the opposite end of the machine the lugs are of uniform length and are properly shaped and cleaned for attachment to so-called straps which join them in 30 groups.

By the present invention the output of the machine is increased, its operation is improved, and the danger of injury to the 35 plates as they are engaged one at a time and conveyed from the feed magazine by cleats of the conveyer is minimized.

In accordance with the present invention, so-called double plates with lugs projecting 40 from both ends are conveyed through the machine by a pair of intermittently moving conveyer chains or equivalent means, and by the provision of two sets of cutting tools past which the double plates are conveyed, 45 and by the provision of a suitable cutting device preferably in the form of a reciprocating punch the two lugs of each double plate are sawed and milled, and the plates are subsequently split in two, and at the same 50 time the cut edges are appropriately shaped so as to provide feet at the cutting plane.

By operating the conveyer chains intermittently, and by properly locating or spacing the feed magazine, the lug cutting tools 55 and the punch, the cleats on the conveyer

chains can be caused to engage the plates in the feed magazine near the start of the intermittent movements so as not to injure them, the plates can be conveyed past the tools which cut and mill the lugs when the 60 plates are moving at substantially their maximum speed, and the punch can be operated between the intervals of movement, in which event the movements of the parts are properly coöordinated, and effective results will be attained.

The invention may be briefly summarized as consisting in certain novel details of construction, and combinations and arrangements of parts which will be described in 90 the specification and set forth in the appended claims.

In the accompanying sheets of drawings wherein I have shown an embodiment of the invention which operates effectively, Figure 75 1 is a side view of the major portion of the machine with certain parts broken away; Fig. 2 is a top plan view with the punch press or plate splitting part removed; Fig. 3 is an end view looking toward the left of 80 Fig. 1; Fig. 4 is a transverse sectional view substantially along the line 4—4 of Fig. 1, looking in the direction indicated by the arrows; Fig. 5 is a sectional view substantially along the line 5—5 of Fig. 1, looking 85 in the direction indicated by the arrows; Fig. 6 is a view somewhat similar to Fig. 1, but omitting many of the parts so as to show more clearly than in Fig. 1 of the operation of the machine; Fig. 7 is a plan 90 view of one of the double storage battery plates which are passed through the machine; and Fig. 8 shows the manner in which the double storage battery plate is split into single plates and the shape of the 95 section which is punched from the middle of the double plate.

The machine includes a main frame 10, on which is mounted all operating parts including the conveying means by which the 100 storage battery plates to be operated on are carried through the machine. In this instance a pair of sprocket wheels 11 are provided at each end of the machine, and these drive two conveyer chains 12 which are arranged side by side and travel at the same speed, said chains consisting of flat plates 12^a connected together by links 12^b. At the top of the machine the plates of the chains 12 travel over guide rails 13, which with 110

the assistance of suitable spacing guides 14, between the chains (see Fig. 5) position the chains properly with respect to the several operating tools.

5 The lower or returning portions of the conveyer chains 12 pass over and are supported by rollers 15 suitably supported between the sides of the frame 10.

At the receiving or feeding end of the 10 machine which is at the left hand end of Fig. 1, a table 16 is provided, a portion only of which is shown, and on this table the plates to be operated on are stacked by an operator. Adjacent the table is a so-called feed magazine 17 which is supported on the sides of the frame and extends across over the conveyer chains 12. This feed magazine contains a vertically adjustable plate 17^a against which the storage battery plates 18 to be operated on, bear, as clearly shown in Fig. 6. The lower outer face of this plate 17^a is beveled or tapered as shown in Fig. 6, so that the plates 18 near the bottom of the stack can become somewhat staggered as indicated 25 in said figure, and the lower edge of the magazine plate 17^a will be just sufficiently above the conveyer chains that the storage battery plates 18 can be fed from the magazine, one at a time, from the bottom of 30 the stack. As is shown in Fig. 2, each plate 18 is supported equally and symmetrically on two oppositely disposed conveyer plates 12^a, with the lugs 18^a which project from opposite ends of the storage battery 35 plates 18, extending beyond the outer side edges of the conveyer chains so that they may be operated on by the cutting tools subsequently to be described. The conveyer plates 12^a are provided at their outer rear 40 corners with L-shaped cleats 12^b which engage the outer rear corners of the storage battery plates 18, and thus at each movement of the chain a plate 18 at the bottom of the stack in the feed magazine is engaged by a 45 pair of these cleats, and by the latter are conveyed forwardly from the feed magazine and are positioned or held in proper position on the conveyer plates until after the splitting operation.

50 As the plates 18 leave the feed magazine they pass under a yieldable or spring-pressed shoe 19, supported on the rear side of the magazine, as shown in Fig. 6, and then they pass under a pair of upper auxiliary belts 55 20, the lower portions of which are engaged by a series of spring-pressed rollers 21 which cause these belts to press the storage battery plates 18 down onto the conveyer chains while the lugs 18^a are being sawed and milled. As the plates 18 are conveyed through the machine, and while pressed down onto the conveyer chains by the belts 20 as just stated, the ends of both lugs 18^a of the plates are sawed off by a pair of rotating saws 22 located alongside the con-

veyer chains, as clearly shown in Fig. 2. After the plates 18 pass the saws 22, the upper and lower faces of both lugs are milled off by being carried between two pairs of milling cutters 23, also located alongside the 70 conveyer chains just beyond the saws 22, the cutters of each pair being located one above the other. The saws are supported on two short horizontal shafts 24 journaled in bearings at the sides of the machine and provided 75 at their outer ends with belt pulleys 25. The milling cutters are supported on short shafts 26 at the outer ends of which are belt pulleys 27. The saws and milling cutters are rotated at high speed by belts 28 and 29 which are provided at both sides of the machine, which belts are driven by pulleys 30 provided at both ends of a horizontal cross-shaft 31 which in this instance is driven by a belt 32 which passes about a driving pulley 33 85 on a lower cross-shaft 34, driven by a motor 35 (see particularly Fig. 5).

After the plates 18 have been carried by the intermittent movements of the conveyer chains, first from the feed magazine, then 90 past the saws, and then between the milling cutters 23, by the further intermittent movements they are carried out from the hold-down belts 20 and then pass under a pair of spring actuated presser plates or strips 36 95 which extend lengthwise of the conveyer chains, and are located one centrally above each conveyer chain. These strips 36 are yieldingly supported from a pair of cross-yokes 37 which are secured to the sides of the 100 main frame and extend across the conveyer chains above the latter. Then while pressed downward and firmly held against the conveyer chains by the presser strips 36, the plates pass over and come to rest, one at a 105 time on the die 38 of a punch press 39 having a vertically reciprocating intermittently operated punch 40 which punches a strip 18^b from the middle of the double plate 18, forming two separate or single plates 18^c. The 110 sections or strips 18^b, cut by the punch and die from the middle of the double plates drop down through the machine and are diverted out to one side by a suitable chute, shown in Fig. 4. It will be observed that the strips 115 18^b thus cut out from the double plates are irregular in shape, the shape of the cut out sections being such as to give the adjacent ends of the single plates the desired contour shown in Fig. 8, and particularly to provide 120 feet or lugs 18^d at the bottom edges of the plates.

Next, by the further intermittent movements of the conveyer chains, the plates are conveyed out from beneath the presser strips 125 36, and finally leave the conveyer chains and preferably pass onto conveyer belts, not shown, which convey them away from the machine or onto any other suitable receiving member.

The punch 40 of the press 39 is carried by a vertically reciprocating cross-head 41 which is reciprocated by a crank or eccentric on a power shaft 42 at the top of the press, 5 which shaft is, in this instance, rotated by a belt 43 driven by a motor 44, shown in Fig. 3.

The punch is operated intermittently through mechanism to be described, which at 10 the proper instants causes the power shaft to be clutched to its driving pulley 45, and then released after the punch is given its downward and then upward stroke. The storage battery plates 18 and the conveyer 15 chains are stationary during the punching or cutting operations, the conveyer chains bringing the plates, one at a time, directly over the die, and remaining stationary during the downward and upward strokes of 20 the punch.

To bring this about, properly coördinated clutch controlling and conveyer actuating mechanisms are required. In this instance the power to intermittently move the conveyer 25 chains and to actuate the clutch controlling the punch press is derived from the motor 35, which as already explained, drives the saws and milling cutters. As will be seen by reference particularly to Fig. 1, this 30 motor 35, through the medium of a belt 46, drives a transverse shaft 47, having a pinion 48 (see Fig. 4) which pinion engages a gear 49 on a transverse shaft 50. This shaft has a pinion 51 which drives a gear 52 on a trans- 35 verse shaft 53 supported at the delivery end of the machine, as shown in Figs. 1, 2 and 3. On the end of shaft 53 opposite that to which the gear 52 is secured, is a crank 54 which is connected by a connecting rod 55 40 to a swinging arm 56 which is loosely mounted on a shaft 57 to which the sprocket wheels 11 at the delivery end of the machine are attached. By the continuous rotation of the crank 54 oscillating movements 45 are imparted to the arm 56, and on each down stroke a spring pressed pawl 58 by engaging a ratchet wheel 59 which is secured to the shaft 57, turns the shaft 57 through a predetermined portion of a revolution, 50 and hence moves the conveyer chains a predetermined amount, which in practice is equal to the distance from the center of one chain plate 12^a to the center of the adjoining plate.

55 In order that the punch press clutch may be operated so as to cause the punch to be lowered as soon as the conveyer comes to rest, I provide on the shaft 53 carrying the rotating crank 54, a cam member 60 with a 60 cam lug 61 which is so positioned that on each revolution of the shaft 53, and at the desired point of each revolution engages a roller 62 which is connected in any suitable manner to operate the punch press clutch, 65 and which in this instance is mounted on an

arm 63 of a rock-shaft 64 (see Fig. 1) having an upstanding arm 65 connected by a link 66 to a bell-crank 67 having a horizontal arm to which a clutch rod 68 is attached, and which extends upward alongside the frame of the 70 punch press to the clutch. It will be understood without showing the details of the clutch, which can be of any suitable form, such as ordinarily employed on intermittently operating punch presses, that the 75 rocking movement imparted to the arm 63 by the cam 60, and the consequent downward movement imparted to the clutch rod 68 is sufficient to cause one revolution of the power shaft of the press so that the punch 80 of the press will be lowered, elevated, and then stopped until the cam 60 again rocks the arm 63 following the next movement of the conveyer chains.

The machine is operated in the following 85 manner: The motors 35 and 44 are started, whereupon the lug cutting saws and lug milling cutters are rotated at high speed, and the conveyer chains and punch press are operated intermittently. The operator 90 places a stack of storage battery plates in the feed magazine, and at each movement of the chains a plate is taken from the bottom of the stack and fed forwardly from the magazine. On leaving the magazine they 95 pass under the yieldable shoe 19 which prevents the rear edges of the plates kicking up from the cleats of the conveyer chains as the plates pass under the hold-down belts 20. Then the plates pass forward step by 100 step, and in so doing the lugs are first carried past the cutting saws and are cut off to the proper length; then between the milling cutters which clean and brighten opposite sides and reduce them to the proper 105 thickness; then they are carried underneath the presser plates or strips 36 directly over the die of the punch press, and while stationary thereon by the action of the punch of the punch press they are divided into 110 two equal sections, and then they are carried on singly or as individual storage battery plates to the delivery end of the machine.

The various operating parts are so located, 115 and the operations of the punch press and conveyer chains are so timed that the cleats on the plates of the conveyer chains engage the storage battery plate at the bottom of the stack at the start of the movement of 120 the conveyer chains and while they are still moving slowly, and the lugs of the storage battery plates are carried past the saws, and during the subsequent movement past the milling cutters at about the middle portions 125 of the conveyer chain movements, or while the plates are being conveyed at approximately the maximum speed. In other words, the intermittent movement imparted to the conveyer chains is not only important 130

in bringing about a cessation of movement during the punching operations, but due to the slow initial movement of the cleats at the time they engage and start moving the

- 5 storage battery plates, no injury is done to the latter as they are engaged by the cleats and started in motion, and at the same time the necessary high speed movement to obtain effective results occurs between the lugs
- 10 of the plates and the rotary tools which operate on them. By reason of these features just mentioned, though rapid intermittent movements are imparted to the conveyer chains so that the output of the machine is
- 15 large, still the parts function in such a manner that the storage battery plates while being handled in the machine are not in the least injured or bent, and danger of clogging the machine is minimized.
- 20 Having described my invention, I claim:

1. In a machine of the character described, a frame, a conveyer for conveying through the machine double storage battery plates with lugs at opposite ends thereof, lug cutting tools arranged along both sides of the conveyer, and a plate cutting device for cutting the plate transversely.

2. In a machine of the character described, a frame, conveying means for conveying 30 through the machine double storage battery plates with lugs at opposite ends thereof, rotary lug cutting tools located at both sides of the conveying means, and a reciprocating plate splitting device located beyond the cutting tools and adapted to cut the plates lengthwise of the direction of feed.

3. In a machine of the character described, a frame, conveying means for conveying through the machine double storage battery plates with lugs at opposite ends thereof, lug cutting tools at both sides of the conveying means, and a plate cutting device arranged beyond the lug cutting tools centrally with respect to the conveying means 45 and serving to divide the double plates by cutting them transversely.

4. In a machine of the character described, a frame, conveying means for conveying through the machine double storage battery plates with lugs at both ends thereof, lug cutting tools located at both sides of the conveying means, reciprocating plate cutting means for cutting the plates transversely thereof and at the same time forming irregular edges on the single plates thus formed.

5. In a machine of the character described, a frame, conveying means for conveying through the machine double storage battery plates with lugs at opposite ends thereof, lug cutting tools located along both sides of the conveying means, and a reciprocating punch located beyond the lug cutting tools between the side edges of the conveying

means for cutting transverse strips from the 65 middle portions of the plates so as to divide them into single plates and to form feet at the cut edges thereof.

6. In a machine of the character described, a frame, conveying means for conveying 70 through the machine double storage battery plates with lugs at opposite ends thereof, lug cutting tools located at opposite sides of the conveying means, a cutting device for cutting the plates transversely into single 75 plates, and means for operating the conveying means.

7. In a machine of the character described, a frame, feed mechanism adapted to receive a stack of double storage battery plates with 80 lugs at opposite ends thereof, conveying means having plate engaging devices for engaging and feeding the plates one at a time from the bottom of the stack and for conveying them through the machine, lug 85 cutting tools located laterally on both sides of the center line of the conveying means, and a plate cutting device located beyond the lug cutting tools centrally of the conveying means for cutting the double plates trans- 90 versely into single plates.

8. In a machine of the character described, a frame, feed mechanism adapted to receive a stack of double storage battery plates with 95 lugs at opposite ends thereof, conveying means having plate engaging devices for engaging and feeding the plates one at a time from the bottom of the stack and for conveying them through the machine, lug cutting tools located laterally on both sides of 100 the center line of the conveying means, a plate cutting device located beyond the lug cutting tools centrally of the conveying means for cutting the double plates transversely into single plates, and means for 105 moving the conveying means intermittently.

9. In a machine of the character described, a frame, feed mechanism adapted to receive a stack of double storage battery plates with 110 lugs at opposite ends thereof, conveying means having plate engaging devices for engaging and feeding plates one at a time from the bottom of the stack and for conveying them through the machine, lug cutting tools 115 located laterally on both sides of the center line of the conveying means, and a plate cutting device located beyond the lug cutting tools centrally of the conveying means for cutting the double plates transversely into 120 single plates, the conveying means comprising two separate conveyer chains arranged side by side and operated simultaneously.

10. In a machine of the character described, a frame, feed mechanism adapted to 125 receive a stack of double storage battery plates with lugs at opposite ends thereof, conveying means having plate engaging de-

vices for engaging and feeding the plates one at a time from the bottom of the stack and for conveying them through the machine lug cutting tools located laterally on 5 both sides of the center line of the conveying means, a plate cutting device located beyond the lug cutting tools for cutting the double plates transversely into single plates, the conveying means comprising two separate 10 conveyor chains arranged side by side and operated simultaneously, and means for operating said chains intermittently.

11. In a machine of the character described, a frame, conveying means for conveying through the machine double storage battery plates with lugs at opposite ends thereof, said conveying means comprising two similar endless conveyers adapted to travel in unison, and provided at regular 15 intervals with cleats for engaging the outer rear corners of the plates, lug cutting tools arranged on opposite sides of said conveyers, a die located between the conveyers beyond the lug cutting tools, a reciprocating punch adapted to coöperate with the die to punch irregular sections from the middle portions of the plates and thereby form single plates with feet at the cut edges, means for driving the lug cutting tools continuously, and means for operating the conveying means 20 and the punch intermittently, the conveying means by its intermittent movements bringing the plates one at a time centrally over the die, and the punch operating on the plates between the intermittent movements. 30 35

In testimony whereof, I hereunto affix my signature.

PAUL E. NORRIS.
